FAST-ACTING AUTOMATIC VOLUME CONTROL AND SYNC PULSE RESHAPING CIRCUIT

Antony Wright, Drexel Hill, Pa., assignor to Radio Corporation of America, a corporation of Delaware

Application June 27, 1945, Serial No. 601,795.

2 Claims. (Cl. 178—7.3)

1

This invention relates to an improvement in television receivers and in one exemplified embodiment to receivers used in connection with telemetering in which the television transmitter is located in an airplane.

When television image signals are transmitted from airplanes, considerable difficulty is encountered by reason of the proximity of the airplane propellers. The presence of the propellers, together with their location, causes an undesired amplitude modulation of the radio frequency carrier, and, in order that these undesired amplitude modulations may be effectively removed so as not to affect the produced image in the receiver, it is necessary to employ a relatively fast-acting automatic volume control in the receiver.

The propeller rotational speeds usually vary between 1,800 and 2,200 revolutions per minute. When a two blade propeller is employed, an undesired amplitude modulation of from 60 to 72 cycles per second is produced. For a three blade propeller this undesired amplitude modulation or variation in transmission is at a rate of from 90 to 108 cycles per second. Unless this undesired amplitude modulation is removed, horizontal bands, which move slowly in a vertical direction at a rate determined by the relation between the television field rate and the undesired modulation rate, are produced on the television receiver screen. To effectively remove the undesired amplitude modulations and to thereby eliminate the presence of these bands on the receiver target area or screen, a fast-acting automatic volume control circuit has been employed, the time constant of the automatic volume control circuit being so chosen as to permit the automatic volume control to remove undesired modulations up to about 200 cycles per second.

For the transmission of information by television under such circumstances, it is sometimes convenient to transmit, for vertical synchronizing, a single vertical sync or synchronizing pulse superimposed upon a somewhat prolonged blanking pulse. By reason of the fast-acting automatic volume control circuit, which is necessary to remove the undesired amplitude modulations, the vertical or field or frame sync impulses, as well as the blanking impulses, are materially attenuated by reason of the fact that the increased carrier amplitude transmitted during the sync and blanking impulse interval is sufficiently long to cause the fast-acting automatic volume control circuit to respond, with the result that the receiver gain is appreciably reduced during the blanking impulse period. By reason of the reduction in gain during the vertical sync and

2

blanking interval as produced by the automatic volume control circuit, the intensity of the vertical sync impulse is materially reduced so that vertical synchronizing frequently becomes difficult.

It is, therefore, the purpose of the present invention to provide a circuit arrangement for use in receivers employing fast-acting automatic volume control circuits whereby the vertical sync impulses may be restored to permit and to assure proper synchronizing of the vertical deflection generators. A separate blanking pulse, generated in the receiver and derived from the deflection pulses which are initiated by the sync pulse, may be used to compensate for the attenuated transmitted pulse.

Another purpose of the present invention resides in the provision of a circuit arrangement for assuring proper operation of the vertical deflection generator in a television receiver, even though the receiver incorporates a relatively fast-acting automatic volume control circuit.

Still another purpose of the present invention resides in the provision of means in a television receiver in which fast-acting automatic volume control is employed whereby the vertical sync impulses, even though attenuated by reason of the automatic volume control, may be restored by an amount sufficient to assure proper operation of the vertical deflection generator.

Various other purposes and advantages of the present invention will become more apparent to those skilled in the art from the following detailed description, particularly when considered in connection with the drawing, wherein the single figure thereof shows a schematic diagram of a preferred form of the present invention.

Referring now to the drawing, a portion of a complete television receiver is shown which includes an antenna 10 for receiving the transmitted signal energy from the television transmitter. This antenna supplies the received signal energy to the portion 12 of the television receiver which includes a radio frequency tuner, the local oscillator, the mixer and the intermediate frequency amplifier. The output from this portion 12 of the television receiver is applied to a demodulator tube 14 which includes an anode 16 and a cathode 18. The load circuit for the demodulator is the resistance element 20 across which video, sync and blanking signals are produced. When the intermediate frequency carrier is applied to the demodulator 14, the demodulated signals are then available from the cathode 18 of the demodulator tube.

The television receiver also includes a limiter tube 22 having a cathode 24 and an anode 26. The cathode 24 of the limiter tube 22 is connected to the cathode of the demodulator tube while the anode 26 of this limiter supplies the output signals to a video amplifier 28. This amplifier includes at least a cathode 30, a control electrode 32 and an anode 34, and, although the amplifier tube 28 is shown as a triode in the circuit diagram, a high gain screen grid or pentode tube would normally be employed. After the television image or video signals have been amplified by the video amplifier (including one or more tubes such as shown at 28) the amplified signals are then applied to the image producing tube, for example a tube of the type known as the "kinescope," by way of conductor 36.

It will be observed that the cathodes of the demodulator 14 and the limiter 22, are maintained at a potential approximately 30 volts negative with respect to ground. This biasing of the cathodes of these two tubes does not in any way affect the demodulator, but, in view of the direct current path through the grid resistance 38 associated with the control electrode 32 of tube 28, a bias is applied between the cathode and anode of the limiter tube 22. This bias normally permits conduction of the limiter tube, but when the amplitude of the demodulated image or video signals present at the cathode of the demodulator is sufficiently positive to overcome the bias of the limiter, conduction through the limiter ceases with the result that disturbances or impulses that would produce undesired high voltage deviations of the video signals are limited and are prevented from being applied to the video amplifier.

The limiter, in addition to supplying disturbance or noise clipped video or image signals to the video amplifier 28 also supplies the signals to an automatic volume control amplifier tube 40 and to the horizontal or line sync signal separating circuits (not shown) by way of conductor 42. The horizontal or line sync signal separator may be of conventional design and is effective for supplying the required sync signals to the horizontal deflection generator for the image producing tube.

The automatic volume control amplifier tube 40 includes a cathode 44, a control electrode 46 and an anode 48. The cathode is connected to ground while the anode is maintained positive with respect to the cathode by a source of positive potential (not shown) and a load impedance or resistance 50. After the signals, as applied to the automatic volume control amplifier 40, have been amplified, they are then applied to the cathode 52 of the automatic volume control rectifier 54 by way of a coupling condenser 56. Automatic volume control potentials are then available from the anode 58 of the rectifier 54. These automatic volume control potentials are applied to the portion 12 of the television receiver by way of conductor 60 and are proportional to the demodulated video signal. Located between the conductor 60 and the anode 58 of the automatic volume control rectifier 54 is an intermediate frequency carrier filter circuit and a time constant circuit including resistors 62 and 64 as well as condensers 66 and 68. By proper choice of the values of these resistors and condensers, the automatic volume control circuit can be made sufficiently fast-acting to effectively remove the undesired amplitude modulations.

Wave forms are also shown associated with the elements in the diagram to assist in explaining

the operation of the circuit arrangement. The transmitted radio frequency energy is shown associated with the antenna 10 and for the purpose of simplicity, this transmitted radio frequency energy does not include any undesired amplitude modulations. The wave form is, therefore, more indicative of the transmitted signal energy than of the actual received signal energy. The curve B associated with the anode 26 of the limiter tube 22 shows a wave form applied to the video amplifier 28 and to the automatic volume circuit amplifier 40. At this particular point in the circuit, the sync signals extend in a positive direction, and, for simplicity, the horizontal or line sync impulses have been omitted. It will be observed, however, that the wave form of the frame or vertical sync impulse is materially different from the modulation wave form and this change in wave form is by reason of the fast-acting automatic volume control circuit. The steep front of the vertical or frame sync impulse is retained since the automatic volume control circuit is ineffective to remove the high frequency represented by the steep front, but the remainder of the vertical or frame sync impulse as well as the immediately following blanking impulse are materially attenuated due to the change produced in the effective gain in the receiver by reason of the action of fast-acting automatic volume control.

The curve C shows the wave form present at the cathode of the automatic volume control rectifier tube 54 and at this point in the circuit the sync impulses extend in a negative direction. It will be observed that a considerable portion of the higher frequency components of the video or image signals have been removed since the circuit parameters associated with the automatic volume control amplifier tube 40 are not particularly designed to pass the higher frequency components of the image or video signal since it is not necessary that these components be present in any of the circuit arrangements associated with the anode of the automatic volume control amplifier tube 40. The steep front of the vertical or frame sync impulse is still retained but considerable attenuation takes place immediately thereafter with the result that the steep wave front or high frequency component appears in the automatic volume control amplifier anode circuit as an integrated pulse with relative low amplitude. The automatic volume control voltage is obtained from the peaks of the sync impulses and are effective for determining the effective gain of the portion 12 of the television receiver.

In order to re-establish the vertical or frame sync impulse to an extent such that it would be effective to properly and satisfactorily synthesize the vertical deflection generator, the voltage variations present at the anode of the automatic volume control amplifier are inverted and amplified by a sync signal amplifier tube 70. The voltage variations, represented by the curve C, are applied to the control electrode of the sync signal amplifier and since the anode 72 of this tube is connected to a source of positive potential by way of a load impedance 74, amplified voltage variations will be present at the anode tube 70. These voltage variations are represented by the curve D, and, at this point in the circuit, the sync impulses extend in a positive direction. After the frame or vertical sync impulses have been sufficiently amplified by the amplifying tube 70, they may then be applied to a sync signal separator tube 76 which includes, in addition to

a cathode, a control electrode 78 and an anode 80. The control electrode 78 of the sync signal separator tube 76 is normally maintained at a negative potential so that the separator tube 76 is biased to cut-off at approximately a point represented by the dotted line 82 associated with the curve D. Only those signals which extend in a positive direction and having an intensity sufficient to overcome the bias potential of tube 76 will be effective to produce a voltage variation at the anode 80 of the separator tube. Since the wave front of the vertical sync impulses normally exceeds this bias potential, they produce voltage variations extended in a negative direction at the anode 80 of the separator tube. These voltage variations are represented by the curve E associated with the anode of the separator tube 76. The output from the vertical or frame sync signal separator tube 76 is then applied to the control electrode 82 of the sync signal amplifier tube 84 where their intensity is increased. Amplified vertical sync signals are then available from conductor 86 associated with the anode of the sync signal amplifier tube 84. The wave form of the voltage variations available at conductor 86 is represented by the curve F associated with this conductor, and the vertical sync impulses extend in a positive direction and have sufficient amplitude to cause proper response and operation of a conventional vertical deflection oscillator (not shown).

In view of the foregoing, it will, therefore, be observed that through the use of the present invention reliable operation of the vertical or frame deflection generator is made possible even though the television receiver includes an automatic volume control circuit which is sufficiently fast in its operation to produce considerable attenuation of the sync impulses. In the absence of such a circuit as described above and shown in the drawing, the intensity and effectiveness of the vertical or frame sync signal is not sufficient to produce reliable operation of a conventional vertical deflection generator. When the present invention is incorporated in a television receiver which is designed to operate under the conditions described above, satisfactory operation may be obtained and the television receiver will remain in proper synchronous operation with the transmitter, even though a fast-acting automatic volume control circuit is incorporated in the receiver for the purpose of removing undesired amplitude modulations in the received radio frequency energy.

In the above description it has been assumed that the line deflection is in a horizontal direction across the target electrode of the camera tube and across the screen of the receiver tube, while the field deflection is in a vertical direction. The present invention could be exercised, however, if these deflection directions were reversed. Under such a condition the frame or horizontal sync impulse would be re-established by the present invention.

I claim:

1. A television receiver including means for receiving and demodulating the radio frequency carrier that has been amplitude modulated by television image signals and by horizontal and vertical sync impulses, an amplifier for amplifying the low frequency components of the image signals and the vertical sync impulses as derived from the carrier demodulator, a rectifier for rectifying the amplified low frequency components of the image signals, a circuit arrangement asso-

ciated with the rectifier for producing fast-acting automatic volume control potentials for removing undesired modulations of the radio frequency carrier of a predetermined low frequency, the said fast-acting automatic volume control circuit inherently functioning to appreciably attenuate the vertical sync impulses immediately following the leading edges thereof, a further amplifier for amplifying the low frequency components of the image signals and the residual leading edge of the vertical sync impulses, an electron discharge tube having a cathode, a control electrode and an anode, means for maintaining a predetermined average potential difference between the control electrode and the cathode, means for applying the amplified signals to the control electrode of said discharge tube with the residual vertical sync impulses extending in a positive direction whereby said discharge tube will operate to separate the amplified leading edge portion of the vertical sync impulses from the image signal, and means for further amplifying the so separated leading edge of the vertical sync impulses.

2. A television receiver adapted to receive a radio frequency carrier that is amplitude modulated by image signals and by horizontal and vertical sync impulses, and in which the carrier may contain, in addition, an appreciable undesired amplitude modulation of a predetermined relatively low frequency, said receiver including a fast-acting automatic volume control circuit for substantially nullifying the effects of the undesired amplitude modulation and in which the fast-acting automatic volume control also results in an appreciable attenuation of the vertical sync impulses immediately following the leading edge portion thereof, comprising an electron discharge tube for amplifying at least the low frequency components of the image signals and the residual leading edges of the vertical sync impulses, means to rectify the amplified low frequency components to produce fast-acting automatic volume control potentials, means to further amplify the low frequency components of the image signals and the residual leading edges of the vertical sync impulses, means including a second electron discharge tube having a cathode, a control electrode and an anode, means to apply the further amplified low frequency components and the residual leading edges of the vertical sync impulses to the control electrode of said tube with the vertical sync impulses extending in a positive direction, means to bias the control electrode negative with respect to its associated cathode whereby amplified leading edge portion of the vertical sync impulses are separated from the low frequency components of the image signal, and means to further amplify the so separated portion of the vertical sync impulses.
